UNITED STATES PATENT OFFICE.

CHARLES SAUER, OF EASTON, MARYLAND.

STUMP-PULLER.

SPECIFICATION forming part of Letters Patent No. 366,032, dated July 5, 1887.

Application filed March 23, 1887. Serial No. 232,103. (No model.)

To all whom it may concern:

Be it known that I, CHARLES SAUER, of Easton, in the county of Talbot and State of Maryland, have invented a new and useful Improvement in Stump-Pullers, of which the following is a specification.

My invention is an improved stump puller seeking to provide a simple and easily-operated construction, whereby to exert the necessary strain; and the invention consists in certain novel constructions and combinations of parts, as will be described and claimed.

In the drawings, Figure 1 is a perspective view of the machine ready for use in the compound form. Fig. 2 is a perspective view showing the improvement in the single or simple form. Fig. 3 is a sectional view showing one of the horizontal bolts for uniting the frame-sections. Fig. 4 is a vertical section drawn alongside the shafts or drums and through the base when the parts are arranged as shown in Fig. 1. Fig. 5 is a detail plan view, on a reduced scale, of the base. Fig. 6 is a detail view of the draft-rods, and Fig. 7 shows the shaft and wear-sleeve.

The base A is, by preference, of the flat form shown, having its edges inclined upward, to facilitate its movement upon the surface of the ground when in use, and its movement along said surface when the device is being moved from point to point in a clearing in order to pull the stumps in different portions thereof. Through this base I form in line with each other four bolt-holes, *a a* and *a' a'*, the two inner holes being lettered *a* and the outer ones *a'*.

The framing proper of the puller is formed in two similar sections, B B, each of which has vertical bearings *b b* for the shafts C C, and is provided with lateral openings or ways at D, for the passage of the pulling chain or rope.

On the frames B, adjacent to the openings D, I provide bearings at *d* for the trunnions *e* of guide-pulley E, which, as will be obvious from the drawings, may be adjusted to any one of the sets of bearings, as may be desired. The bearings *d* are preferably eyes, as shown, and it is preferred to journal said eyes to the frame or frames B, so they may be turned horizontally to serve as bearings for the vertical guide-pulley or vertically to receive the horizontal rods F, which connect the anchor-guy G with the machine. This guy consists of a clevis, *g*,

and the four rods *g'*, connected at one end with the clevis *g*, and having openings at their opposite ends to receive the rods F, by which the guy is connected with the frames. This guy may be applied to either the single framing shown in Fig. 2 or the compound framing shown in Fig. 1, the guy being connected with the framing, as most clearly shown in Fig. 2.

Through the frame-sections B B, I form coincident bolt-holes at *h*, for the bolt-rods H, which have heads *h'* at one end, and are adapted at their opposite ends to receive nuts *h''*, or other suitable or equivalent fastenings. By means of these bolt-rods the sections B may be firmly united together.

In securing the frame to the base the bolts I I are passed through the bolt-holes *i* in the section or sections through the bolt-holes *a* or *a'* in the base. When a single section B is used, the bolt I may be passed through the side bearing of same and through the openings *a a*, whereas when the compound form of frame is employed the bolts are usually passed through the outer holes of each section, and thence through the holes *a' a'*; but manifestly, when so desired, the bolts may be passed through all of the holes, four bolts being thereby employed when the compound frame is employed. The shafts C C are provided at their upper ends with portions to receive the sweep C', and these shafts, when the compound frame is employed, are geared together, it may be by wheel gearing, as shown, by sprocket-wheels and belt, or in other suitable manner.

On the shaft C, which receives the chain, I employ a wear-sleeve, J, having openings *J'*, and secured by pins *j*. By preference I form this sleeve, as shown, of three bands, *j'*, and four bars or uprights, *j''*, such parts being securely connected by rivets *j'''*, or by welding, or in other suitable manner. This sleeve is employed when chains are used, and in addition to avoiding the wear on the shaft it, by reason of its cross sectional shape, conforms to the chain and receives the same, rendering the chain less likely to break. When a rope is used, this wear-sleeve is omitted.

It is manifest that in drawing a stump some distance from the machine the weight of the chain is a great impediment, and to, in part at least, avoid this objection I provide the draft-

rods K, having loops K' at their ends, the said loops being formed with an end portion or neck, k, and an enlarged portion in rear of said neck. The chain may be united with one of 5 the necks, as shown at x in Fig. 1, and the ends of two adjoining rods may be connected by means of mortised joint-blocks L and bolts l, as will be understood from Fig. 6. By this construction the chain can be quickly lengthened at will, whereas, by means of the short draft-rod, (shown at y in Fig. 1,) the shank of the chain may be taken up, as desired.

By reason of the peculiar form of anchorage of the machine it will in starting to pull a 15 stump swing around into direct line with said stump.

In pulling small stumps the single frame may be employed, while for larger stumps and other heavier objects the compound frame may 20 be conveniently geared up for use.

Manifestly the machine is adapted for use in moving houses, rocks, or other heavy objects, as well as for the extracting of stumps.

Having thus described my invention, what I 25 claim as new is—

1. A machine, substantially as described, having a frame formed in sections, combined with connections for uniting said sections and the moving parts of each of said sections, such 30 moving parts being geared together, substantially as set forth.

2. The combination, in a machine substantially as described, of the base, the frame-sections, connections for uniting said sections, and 35 fastenings for securing the same to the base, substantially as set forth.

3. In a machine substantially as described, the combination of the frame B, having openings or ways D and provided adjacent the 40 same with bearings d, the drum or shaft journaled in said frame, and the guide-pulley E,

having its trunnions fitted to bearings d and adjustable into one or the other of said sets of bearings, substantially as set forth.

4. The combination of the frame having eyes, 45 d, the anchor-guy having rods g', and the rods F, extended between eyes d, substantially as set forth.

5. In a machine substantially as described, the combination of the frame, the shaft or 50 drum journaled therein, the eyes d, journaled in the frame, the guide-pulley, the anchor-guy having rods g', and the rods F, substantially as set forth.

6. The improved stump-puller herein described, consisting of the base, the frame formed in sections, connections for uniting said sections, fastenings for securing the frame to the base, the shafts journaled in the frames and 60 geared together, and the anchor-guy, substantially as set forth.

7. In a stump-puller, a draft-rod having a 65 loop, K', provided with a neck, k, and having an enlarged portion in rear of said neck, substantially as set forth.

8. A machine substantially as described, comprising a frame formed in detachable sections B B, shafts journaled one in each of said sections and geared together, and connections uniting said sections B B, substantially as set 70 forth.

9. In a machine substantially as described, the combination, with the frame-sections B B, of the rods H H, forming connections for uniting said sections and extended through the 75 said sections, whereby to brace them, substantially as set forth.

CHARLES SAUER.
